INVENTOR

J. G. Kitchell

BY

Conrad C. Billings ^{his} ATTORNEY

UNITED STATES PATENT OFFICE.

JOSEPH G. KITCHELL, OF HADDAM, CONNECTICUT.

PICTURE AND PROCESS OF MAKING THE SAME.

1,269,458.

Specification of Letters Patent. Patented June 11, 1918.

Application filed February 21, 1916. Serial No. 79,555.

To all whom it may concern:

Be it known that I, JOSEPH G. KITCHELL, a citizen of the United States, and a resident of Haddam, county of Middlesex, and State 5 of Connecticut, have invented certain new and useful Improvements in Pictures and Processes of Making the Same, of which the following is a specification.

This invention relates to new and im- 10 proved art products—pictures and the pro- cesses of making the same.

The present invention is supplemental to that disclosed in my Patent No. 1,144,964, granted June 29th, 1915, upon an application 15 filed December 24th, 1913, and is the result of progressive work in this art.

In general terms the process to be followed in carrying out my present invention as well as that which was followed in the invention 20 of my patent, consists in making a drawing or design in any well known manner upon a suitable fabric which is of such character that it is more or less transparent or translucent. Upon another medium I place the 25 principal details of the design or picture borne upon the first mentioned fabric, which details are colored in order to give correct color values to the design. The fabric or medium bearing the design is superposed 30 over the color design, the two designs being held in register with each other.

Referring to the drawings;

Figure 1 is a front view of the transparent medium having thereon the picture 35 and principal details of an uncolored design or picture shown in reverse position from that of Fig. 2.

Fig. 2 is a front view of the opaque medium with a similar picture thereon to which 40 the colors are applied.

Fig. 3 is a section through the complete article provided with a supporting mat.

Fig. 4 is a section through a complete article having an embossed bead formed around 45 the edge of the under or opaque medium.

Fig. 5 is a section of a complete article with the embossed bead or ridge extending from a frame carrying the upper translucent or transparent medium.

50 Fig. 6 is a section of a three ply upper plane made of two sheets of thin paper between which is secured a sheet of celluloid or other like material.

Fig. 7 is a section of comparatively heavy paper or celluloid or similar material with 55 a monochrome or neutral image on one side and the colors on the other side.

I find that the so called atmospheric effect of such picture is enhanced by a slight separation between the plane of the two 60 mediums which superpose each other. This can be accomplished by means of a mat or frame 10 or any similar device being placed between the two mediums, so that the one medium A is held in a separated position 65 from that of the other medium B as clearly shown in Fig. 3. The same result can be accomplished in a very easy and desirable way by either embossing or pressing out a border 11 from the surface of the lower 70 medium or under plane B to the proper degree of elevation, as shown in Fig. 4, or else embossing or pressing downward a ridge 12 from a supporting mat or frame 10 carrying the upper or translucent or 75 transparent plane or medium A as shown in Fig. 5. By these two latter features these structures do away with the necessity of providing an additional piece or element as a mat.

I have found that sheets of various sorts of paper coated or impregnated with paraffin and then sensitized for the purpose of making photoprints is an efficient method of making the upper or translucent plane, 85 and that this is very effective and easy to operate for certain kinds of work.

Another efficient means of obtaining the transparent or translucent medium, or that medium which carries the neutral composition, is to use a regular positive made from a photograph negative produced either on celluloid, gelatin, glass or any other suitable substance varying in its thickness as the effects seem to require. A glass dry plate 95 with one side ground, frosted or sand blasted makes a very good upper plane.

Another efficient upper medium is produced by incorporating a material like Japan paper or silk, or any similar material with a stiffer medium as a background, as for instance, celluloid, insoluble gelatin or a heavy paper made translucent or transparent by an acid or paraffin treatment.

I have found that it is possible to pro-

duce some very beautiful effects by using as the upper or translucent plane or medium A a structure obtained by taking two sheets of thin paper 15 and 15' and securing between them a clear sheet of celluloid or similar material 16, thereby making a three-ply sheet, as illustrated in Fig. 6.

Another very efficient method of obtaining a so called sub-chromatic effect is to use a comparatively heavy paper or celluloid or a similar material D, first making it transparent, then placing the outlines of the image as at 20 on one side and the colors in proper registration on the reverse side as at 21. This structure is illustrated in Fig. 7.

I have found it very desirable to add in places to the outlines of the design on the transparent or translucent medium where it makes the picture more effective or truthful to nature, a little white pigment or paint or ink or similar material to bring out contrasts, and I have also found it helpful and effective to use other colors in greater or less degree to enhance the color work underneath.

It is apparent that changes may be made without departing from the spirit or scope of my invention. I have shown and described what I consider to be at the present time, the best embodiments of my invention, but it is to be understood that the features shown in the drawing and herein described are illustrative, merely, and I do not intend the invention to be in any way restricted, save as specified in the subjoined claims.

Having now described my invention, what

I claim as new and desire to secure by Letters Patent, is:—

1. A design or picture consisting of an opaque medium having color values thereon, a transparent medium having merely the outlines of the design or picture thereon, a ridge extending from one of the mediums at its edge, the other medium being secured to the ridge, the designs being in substantial register. 40

2. A design or picture consisting of an opaque support or mounting having color values placed thereon, a transparent medium having the contours or principal details thereon in contrasting shades, the two mediums secured to each other with the designs in register. 45

3. A design or picture consisting of an opaque support or medium having color values placed thereon, a transparent medium having the contours or principal details thereon in varying colors, the two mediums secured to each other with the designs in register. 50

4. A design or picture consisting of an opaque support or medium having color values thereon, a transparent medium having the principal details of the designs in black and white, the two mediums secured to each other with the designs in register. 55

In witness whereof I have hereunto set my hand at the borough of Manhattan, city, county and State of New York, this 16th day of February, 1916.

JOS. G. KITCHELL.

In presence of—

ISABEL R. RICHARDS,
ETHEL D. BARON.
